UNITED STATES PATENT OFFICE.

GEORGE W. MCNAUGHT, OF GLIDDEN, IOWA.

DESIGN FOR A DISPLAY-STAND.

SPECIFICATION forming part of Design No. 30,542, dated April 11, 1899.

Application filed February 24, 1899. Serial No. 708,739. Term of patent 14 years.

To all whom it may concern:

Be it known that I, GEORGE W. MCNAUGHT, a citizen of the United States, residing at Glidden, in the county of Carroll and State of Iowa, have invented and produced a certain new and original Design for Display-Stands; and I do declare the following to be a full, clear, and exact description of the invention, such as will enable others skilled in the art to which it appertains to make and use the same.

The invention has relation to a new and useful design for display-stands; and it consists of a design of the configuration shown in the accompanying drawing, in which the figure is a perspective view of the display-stand.

The leading features of my design comprise the sill 1, the end 2, the shelf 3, the bins 4, the ornamental posts 5, rising above the shelf and supporting a shelf 6, and the blocks 7, supported upon the shelf 3 and arranged in a pyramidal manner.

What I claim is—

The design for a display-stand, as herein shown and described.

In testimony whereof I have hereunto set my hand in presence of two subscribing witnesses.

GEORGE W. MCNAUGHT.
